UNITED STATES PATENT OFFICE

ROBERT F. JAMES, OF GARRETT, INDIANA

AUTOMOBILE WINDOW SCREEN

Application filed December 26, 1928. Serial No. 328,480.

This invention relates to an automobile window screen embodying frame sections in which the wire mesh material of the screen is secured, novel means being provided for connecting the sections so that they may be adjusted laterally for use in connection with window frames of various widths.

An important object of the invention is to provide a window screen of this character having an awning section along the upper edge thereof for protection of the occupants of the automobile, against sun rays.

A still further object of the invention is to provide a screen which may be readily and easily positioned in the usual window frame, eliminating the necessity of securing the device by the use of bolts, screws or other auxiliary securing means.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawing:

Figure 1 is a side elevational view illustrating a screen constructed in accordance with the invention as positioned in a window frame of an automobile.

Figure 2 is a vertical sectional view thereof.

Figure 3 is a sectional view taken on line 3—3 of Figure 1.

Referring to the drawing in detail, the screen embodies sections 5 and 6 respectively, the section 5 being formed of a length of sheet metal having its upper edge bent downwardly as at 7 and spaced from the main portion to provide a space for the reception of the upper edge of the section 6, or cooperating section.

The downwardly extended portion 7 extends laterally as at 8 to provide an awning section along the upper edge of the screen frame, the outer edge of the portion 8 being rolled inwardly as at 9.

The lower edge of the section 5 is bent upwardly upon itself from where it extends downwardly in spaced relation with the upwardly extended portion, defining a flange 10 to be fitted over the upper edge of the usual movable window of a motor vehicle, and which in the present showing is indicated by the reference character 11.

The section 6 is also formed of a length of sheet metal having its upper edge bent downwardly and laterally defining an awning section 12, the extreme outer edge of the section 12 being rolled inwardly as at 13 to fit over the rolled edge 9 of the adjacent screen section 5. As shown, the lower edge of the section 6 is bent downwardly and upwardly as at 14 defining a space to permit the section 6 to be slid over the section 5, it being understood that the downwardly extended portion or lower edge of the section 5 rests within the upturned edge formed along the bottom of the section 6, to hold the sections 5 and 6 together in such a way as to permit of sliding movement with respect to each other.

Secured to each section is a length of wire mesh material indicated at 15, there being provided securing strips 16 positioned over the edges of the wire mesh material, the strips being secured by means of rivets 17.

A handle 18 is secured to the inner surface of the device so that the device may be easily handled for positioning in the window opening of a door.

From the foregoing it will be obvious that due to the construction shown and described the upper edge of the screen may be positioned in the usual window groove of the window frame of an automobile door, while the lower edge of the screen is positioned over the upper edge of the window, and the window moved upwardly to set up a binding action between the window frame, screen and window, to the end that the screen will be securely held against movement.

It will also be seen that the screen sections may be moved longitudinally with respect to each other to adjust the screen for use in connection with window frames of various widths.

I claim:

A removable screen for motor vehicle windows, including slidably connected sections, each section embodying a metallic frame having a wide upper member bent downwardly upon itself providing a flange to fit into the window groove of a car window, said wide upper member extending downwardly and outwardly to provide an awning, means at the lower edges of the sections to be fitted over the upper edge of a window, and a wire mesh covering for the frame.

In testimony that I claim the foregoing as my own, I have hereto affixed my signature.

ROBERT F. JAMES.
